UNITED STATES PATENT OFFICE.

JACOB FRED SCHOELLKOPF, OF DALLAS, TEXAS.

DRILLING AND RIVETING MACHINE.

1,299,788.

Specification of Letters Patent.

Patented Apr. 8, 1919.

Application filed November 4, 1918. Serial No. 261,153.

To all whom it may concern:

Be it known that I, JACOB FRED SCHOELLKOPF, a citizen of the United States, residing at Dallas, in the county of Dallas and State of Texas, have invented certain new and useful Improvements in Drilling and Riveting Machines, of which the following is a specification.

This invention relates to new and useful 10 improvements in drilling and riveting machines.

The purpose of the invention is to provide means for drilling a hole through two or more pieces of material which are to be riveted together so as to provide a hole for the rivet, and further to drive a rivet through the hole and upset the end of the same whereby the parts are fastened together. It is particularly sought to carry 20 out these operations continuously and without moving the work after it is once placed in position until the riveting is completed.

In carrying out the invention I provide a machine or apparatus having a support on 25 which the work is positioned. Previous to the positioning of the work a washer or bur is placed on the work support so as to be under the work; however if the style of rivet used does not require a washer the same is omitted. A clamping plunger is mounted so as to be forced down on to the work to hold it in place. A drill works 30 through the plunger and is lowered to drill the hole through the material which is to be riveted. After the hole is drilled the drill is raised and the plunger is raised so that the point of the rivet may be placed in the hole. The plunger is again lowered and acts to drive the rivet through the material and hold the rivet as well as the work 35 in position. A finishing tool is mounted in the work support so as to be elevated and cut off the projecting end of the rivet and at the same time upset said end whereby 40 the head is formed, thus completing the riveting operation.

It is obvious that various structures could be evolved for carrying out the invention and variations made in the general arrangement above described. It will be seen that the drilling and riveting operations may be expeditiously carried out and a much more satisfactory job had than where the work is done by hand. Other details of the 55 invention will be hereinafter more specifically brought out.

The invention will be more readily understood from a reading of the following specification and by reference to the accompanying drawings, in which an example of the 60 invention is illustrated, and wherein—

Figure 1 is a side elevation of a machine constructed in accordance with this invention,

Fig. 2 is a front elevation of the same, 65

Fig. 3 is an enlarged sectional detail of part of the forward portion of the machine illustrating the drill and finishing tool in elevation.

Fig. 4 is a detail of the plunger showing 70 the discharge opening for the drill chips.

Fig. 5 is a sectional detail of the same.

Fig. 6 is a cross sectional detail on the line 6—6 of Fig. 5.

Fig. 7 shows a section of three pieces of 75 material with a hole drilled through the same,

Fig. 8 shows the same material with the rivet and washer in place,

Fig. 9 shows the rivet headed and the 80 work complete,

Fig. 10 is an enlarged plan view of the finishing tool, and

Fig. 11 is an elevation of the same.

In the drawings the numeral 1 designates 85 a pedestal which rises from a circular base 2 and carries a cap 3 at its upper end. A yoke shaped head 4 is fastened on the cap and has the greater portion of its length projecting forward with relation to the pedestal. 90 The head comprises a horizontal work table 5 and an arm 6 overhanging the same. The arm 6 terminates at its forward end in a vertical sleeve 7. A vertically reciprocating hollow plunger 8 slides through the sleeve 95 and has a shouldered ferrule 9 secured in its lower end.

A standard 10 is bolted on the arm 6 and extends upward from the same. A lever 11 is pivoted in the standard and has its forward end directed upwardly and pivotally engaged with a collar 12 fixed on the upper end of the plunger. The rear portion of the lever 11 is curved in harmony with the head 4 and has pivotal connection with a depending link 13. The lower end of the link 13 is pivoted to the upper end of the angular arm 14 of a foot lever 15 extending through the base of the pedestal and pivoted between ears 16. The lever 15 carries a foot plate 17, 110 and when it is desired to lower the plunger 8 the operator places his foot on the plate 17

and swings the forward end of the lever 15 downward whereby the rear arm 14 is elevated. This in turn swings the rear end of the lever 11 upward by means of the link 13, whereby the forward end of the lever 11 is swung downward. When the operator removes his foot from the plate 17 the weight of the lever 11 will return the parts to their normal position. The lever 11 carries a 10 pending boss 18 which engages a stop 19 on the arm 6 thus limiting the return movement of said lever as well as limiting the upward movement of the plunger.

A work support 20 is provided with a reduced shank 21 which fits in an aperture 22 in the lip 23 of the work table 5. The support is located directly under the plunger and has a concentric seat 24 in which the washer or bur 25 may be placed. The support has a central passage 26 extending through its shank. In Fig. 3 I have indicated in dotted line three pieces or layers of material A, B and C respectively as disposed on the support 20 in position to be riveted together. The support thus becomes the work support. The plunger is indicated in dotted lines as depressed so that the ferrule 9 is pressing on the upper layer A.

The plunger is hollow or tubular so as to provide a passage for a depressible drill shaft 27. The drill shaft extends through a bracket 28 projecting from the head of the standard 10 and up through another bracket 29 spaced above the bracket 28. At its upper end the shaft carries a single ball bearing 30 confined in a cap 31. A hand lever 32 pivoted in an arm 33 on the standard 10 rests on the ball 30 and projects forward from the same. A coiled spring 34 encircles the drill shaft between the head 31 and the bracket 29. A stop collar 35 fixed on the bracket 29 surrounds the lower portion of the spring 34 and is impinged by the cap 31 when the drill shaft is depressed, thus limiting the downward movement of said shaft. It is obvious that the shaft is depressed by swinging the hand lever downward. The drill shaft is revolved by a beveled pinion 36 mounted on the bracket 28, the shaft having a key-way 37 (Fig. 3) which permits the reciprocation of said shaft while the same is rotating. A chuck 38 is driven into the lower end of the drill shaft and carries a depending drill 39 normally concealed within the plunger above the ferrule 9. The ferrule 9 has a central passage 40 through which the drill may freely pass.

After the layers A, B and C have been placed on the support 20 and the plunger 8 lowered so that the ferrule 9 clamps the said layers in position the operator grasps the handle lever 32 and depresses the drill shaft so that the drill 39 is projected through the passage 40 and enters the top layer A. The layers are drilled in succession and the

drill passes through the layer C into the passage 26, but only to a limited extent as the cap 31 impinges the collar 35 and limits the downward movement of the drill. The operator releases the hand lever 32 and the spring 34 which has been compressed elevates the drill shaft and raises the drill back into the plunger.

During this drilling operation the operator keeps his foot on the plate 17, and after the hole is drilled, as shown in Fig. 7, he releases the foot lever so that the plunger is raised from the work. This enables him to quickly insert a rivet 41 in the hole and then drive the same through the layers by again depressing the plunger. The point of the rivet is carried through the washer 25, as shown in Fig. 8. The cutting off and upsetting of the end of the rivet remains to be

85

For finishing and heading the rivet a finishing tool 42 is employed. This tool is what might be termed an inverted drill and its head or cutting end is shown in detail in Figs. 10 and 11. The top of the drill is dished out and formed with a central depression 43 from which cutting edges 44 radiate, the cutting edges being associated with V shaped clearance gaps 45. The function of this tool is to cut off a portion of the protruding end of the rivet and spin or upset the remainder into a head such as is shown in Fig. 9. The cutting is carried out, of course, by the cutting edges 44; while the dish shape of the tool in conjunction with the depression 43 carries out the upsetting or spinning operation. The tool, of course, is rotated and applied to the end of the rivet with considerable pressure.

The tool 42 is formed integral with a shaft 46. The shaft 46 passes through a pinion 47 and has a slot 48 receiving a pin 49 fastened in said pinion; whereby the shaft may be moved vertically as it is rotated. The pinion 47 is supported on a bracket 50 secured to the forward end of the table 5 under the lip 23. The shaft 46 projects below the bracket 50 and carries a single ball bearing 51 in its lower end. An eccentric 52 is fixed on a rock shaft 53 mounted in a hanger 54 depending from said bracket. The eccentric has a circumferential groove 55 positioned to receive the ball 51 when the eccentric is rotated. It is obvious that by rotating the eccentric the shaft 46 is elevated thus bringing the tool 42 into engagement with the protruding end of the rivet and finishing same. The shaft 53 projects beyond the hanger 54 and carries a hand lever 56. The operator rotates the eccentric and elevates the tool shaft by pulling upward with the lever 56. It is obvious that he may thus exert considerable pressure on the end of the rivet and the latter being made of soft metal will readily form a head. The upper end

75

of the shaft 46 is shouldered which limits its upward movement by engaging with the underside of the lip 23 and thereby preventing the tool 42 from removing too much of 5 the end of the rivet.

I provide a radial hole 57 in the support 20 through which the chips cut from the end of the rivet are discharged. It is evident that the drill 39 would carry some of the 10 drill chips up into the plunger and deposit the same above the ferrule 9. In order that these latter may be discharged I cut an inclined notch 58 in one side of the ferrule and provide an opening 59 in the plunger 15 registering therewith. The inclined notch will aid in the discharge of the drill chips through the opening 59.

For driving the pinion 47 I provide a beveled gear 60 driven by a sprocket 61 mounted 20 at one side of the bracket 50. The sprocket 61 is driven by a chain 62 from a sprocket 63 mounted on a counter shaft 64, supported transversely of the machine in standards 65 mounted on a bracket 66 projecting rear- 25 wardly from the pedestal 1. The shaft 64 is suitably driven at the required speed. A pulley 67 is mounted fast on the shaft 64 and drives a belt 68 which extends up to and drives a pulley 69 mounted on a shaft 70 30 carried in a bracket 71 supported between the brackets 28 and 29. The shaft 70 carries a beveled gear 72 on its inner end which drives the pinion 36. It will be seen that the drill shaft 27 and the tool shaft 46 are 35 constantly revolved.

Rivets of various lengths and diameters may be used and in such cases drills of various diameters would be employed. Interchangeable supports 20 would be used for 40 rivets of different diameters and different sizes of finishing tools would also be required. While I have illustrated a solid end rivet it is within the province of the invention to use either kinds of rivets and modify 45 the structure accordingly.

What I claim is,

1. In a drilling and riveting machine, a work support, movable means located above the support for holding the work on the support, means for drilling a hole through the work, and means operating through the work support for cutting off the end of the rivet depending from the work and heading said rivet.
2. In a drilling and riveting machine, a work support, movable means located above the support for holding the work on the support, means for drilling a hole through the work, and a finishing tool operating 60 through the work support for cutting off the end of the rivet depending from the work and heading said rivet.
3. In a drilling and riveting machine, a work support, movable means located above 65 the support for holding the work on the

support, means for drilling a hole through the work, and a rotating finishing tool vertically movable in the work support, said tool being constructed to head rivets.

4. In a drilling and riveting machine, a 70 work support, movable means located above the support for holding the work on the support, means for drilling a hole through the work, a rotating finishing tool vertically movable in the work support, said tool being constructed to head rivets, and means for lifting the tool and exerting a pressure thereon.

5. In a drilling and riveting machine, a 80 work support, movable means located above the support for holding the work on the support, means for drilling a hole through the work while the same is on the work support, and means movable vertically of the work support for finishing the end of 85 a rivet.

6. In a drilling and riveting machine, a work support, a vertically movable plunger sustained above the work support, a rotating vertically movable drill sustained above 90 the work support, means for depressing the plunger to clamp work on the work support, means for depressing the drill to bore a hole through the work, a rivet finishing tool located under the work support and 95 movable vertically to finish the end of a rivet depending from the work, and means for elevating the finishing tool.

7. In a drilling and riveting machine, a 100 supporting structure, a work support mounted on the structure, a rotating vertically reciprocating plunger mounted in the supporting structure, a rotating vertically reciprocating drill member depressible through the lower end of the plunger, a 105 lever mounted on the structure and connected with the plunger for depressing the same, a hand lever mounted on the structure and engaging the drill member, means for rotating the drill member, the work 110 support having a vertical passage therethrough, a finishing tool carried by the structure and movable vertically in the passage of the work support, said tool having its upper end provided with cutting edges 115 and dished to upset the end of a rivet, means for rotating the tool, and means for elevating the tool.

8. In a drilling and riveting machine, a 120 supporting structure, a work support mounted on the structure, a rotating vertically reciprocating plunger mounted in the supporting structure, a rotating vertically reciprocating drill member depressible through the lower end of the plunger, a 125 lever mounted on the structure and connected with the plunger for depressing the same, a hand lever mounted on the structure and engaging the drill member, means for rotating the drill member, the work 130

support having a vertical passage therethrough, a finishing tool carried by the structure and movable vertically in the passage of the work support, said tool having 5 its upper end provided with cutting edges and dished to upset the end of a rivet, means for rotating the tool, a lifting lever for the tool, and a device operated by the lifting lever for elevating the tool.

10 9. In a drilling and riveting machine, a head, a work table under the head, a work support having a washer seat and a central passage mounted on the work table, a tubular plunger mounted in the head over the 15 work support, a lever mounted on the head and connected with the plunger for depressing the same, foot operated connections attached to the plunger lever for swinging the same, a ferrule mounted in the lower end 20 of the plunger and having a central passage, a drill shaft mounted in the plunger, a sup-

port mounted on the head and sustaining the drill shaft, a drill mounted in the lower end of the drill shaft and adapted to be projected through the passage of the ferrule 25 when the drill shaft is depressed, a hand lever mounted on the support and engaging the drill shaft for depressing the same, a coiled spring surrounding the drill shaft and normally supporting the same in its elevated position, means for limiting the depression of the drill shaft, means for rotating the drill shaft, a finishing tool movable vertically in the passage of the work support, means for rotating said tool, a lifting device supported by the work table for lifting the finishing tool, and a lifting lever connected with the lifting device for operating the same.

In testimony whereof I affix my signature. 40

JACOB FRED SCHOELLKOPF.
